UNITED STATES PATENT OFFICE.

ADOLPH P. GUSTAFSON, OF CHICAGO, ILLINOIS, ASSIGNOR TO M. SCHULZ COMPANY, OF CHICAGO, ILLINOIS, A CORPORATION OF ILLINOIS.

PNEUMATIC ACTION.

Application filed November 28, 1919. Serial No. 341,146.

To all whom it may concern:

Be it known that I, ADOLPH P. GUSTAFSON, a citizen of the United States, residing at Chicago, in the county of Cook and State of Illinois, have invented a certain new and useful Improvement in Pneumatic Actions, of which the following is a full, clear, concise, and exact description, reference being had to the accompanying drawings, forming 10 a part of this specification.

My invention relates to pneumatic actions, particularly such as are used in pneumatic piano players and player pianos.

One of the objects of the invention is to 15 provide a simple, practical and advantageous construction of pneumatic action of the kind mentioned.

Another object of the invention is to secure simplicity of construction and low cost 20 of manufacture.

Another object of the invention is to obtain compactness of construction so as to reduce the necessary space occupied by the 25 action.

Another object of the invention is to obtain quickness and accuracy of operation, and also to secure a high degree of power.

Another object of the invention is to secure the foregoing and other desirable results in a simple and expeditious manner.

In the accompanying drawings Fig. 1 is a plan view of a portion of a pneumatic action embodying my present invention;

Figs. 2 and 3 are cross sections taken on 35 lines 2-2 and 3-3, respectively, in Fig. 1;

Fig. 4 is a cross section taken on line 4-4 in Fig. 2;

Fig. 5 is a view similar to Fig. 1 of a modified form of device;

Fig. 6 is a cross section taken on line 6-6 in Fig. 5;

Figs. 7 and 8 are cross sections taken on lines 7-7 and 8-8, respectively, in Fig. 6.

Referring to the drawings and especially 45 to Figs. 1 to 4, inclusive, I show a pneumatic action in which there is a longitudinally extending member 1 in the nature of a wind chest which is understood to be connected with the wind inducing apparatus

50 of the instrument, as for example, the bellows ordinarily operated by the feet. The member 1 shown is preferably a metal pipe of more or less rectangular cross section, as shown in Fig. 2.

55 At one side of the member 1, at intervals

along the same there are arranged members 2-2, each one of which is provided with or contains a valve mechanism for a power pneumatic. Below these members 2-2 are situated the power pneumatics 3-3 which are to be controlled and operated by means of the valve mechanisms in the structures 2-2.

The members 2-2 preferably have their ends abutting against one side of the member 1, as shown in Fig. 2, some suitable material such as a layer of felt 4 being interposed between the ends of said members 2 and said member 1. Said members 2 are preferably secured to the member 1 by means of a threaded bar or rod 5 passing transversely through said member 1 and thumb nuts 6 on the threaded ends of said rods 5.

Pneumatics 3-3 are preferably extended 75 underneath the members 2-2 and also underneath member 1 and even to one side of the latter. These pneumatics 3-3 are understood to be power pneumatics for applying power to operate instrumentalities, as for example, for operating the stickers of a piano action to cause operation of said action. Each pneumatic has an upper portion 3^a which is fixed, as for example by being rigidly secured to the under side of the members 1 and 2, and also has a lower portion 7 which is pivoted along one of its longitudinal edges instead of being pivoted at one of its crosswise edges or ends, as has heretofore been done in this art. Thus said swinging member 7 may swing about said longitudinal edge as a pivot or hinge, as shown in Fig. 3, it being understood that there is flexible material 8 extended between the members 3^a and 7 to permit such operation. 85 As a matter of preferred construction a small longitudinally extending member 9 is placed inside of each pneumatic 3 and the member 7 thereof hinged to said member 9 so as to somewhat amplify the extent of swinging or pivotal motion on the part of the member 7. Each swinging member 7 is preferably provided with a projecting member 10 for engaging a projection or abutment on an article or device to be operated, as 90 for example the sticker of a piano action. 100

As a valve arrangement for operating each pneumatic 3, each member 2 is provided with a valve chamber 12 preferably formed in the material of said member 2 110

and adapted to contain an operating valve 13. The chamber 12 is preferably closed to an extent to retain the valve 13 in place by means of the dislike closure 14, preferably 5 made of pasteboard or similar material and having an opening 15 providing a port to be controlled by the valve 13. The valve chamber 12 has a passage or duct 16 opening into its underside which duct or passing 10 sage is preferably provided by a metal sleeve or tube section 17, the upper end of which is preferably turned over at 18 to form a raised or projecting part to provide a valve seat for the valve 13.

15 Another chamber 19 is provided in each member 2, being also preferably formed in the material thereof, and in such chamber 19 there is located a small or supplemental pneumatic 20. This pneumatic 20 is for the 20 purpose of controlling the valve 13 and is to such end preferably provided with a fixed member 21 and a swinging member 22, the latter being uppermost and located below the metal sleeve or collar 17. A suitable 25 connection 23 preferably in the form of a screw extends between the swinging member 22 and the valve 13, in the arrangement shown said screw 23 being screwed into said upper member 22 and having its head fitted 30 into the recess 13^a in the valve 13. Thus the operation of the swinging member 22 will cause the operation of the valve 13.

The chamber 19 in which the small pneumatic 20 is located is connected by a passage 24 with the interior of the wind chamber member 1. As a preferred arrangement 35 the metal sleeve or tube 25 is fitted into a bore or hole formed in the material by the member 2 and is also fitted into an aperture 40 in the side of the member 1. The rod 5 by which the members 1 and 2 are secured together is preferably secured to a sleeve 26 fitted in the bore forming the passage 24.

45 The swinging member 22 is provided with a bleed 27 preferably formed by a metallic nipple 28 set in an aperture formed in said member 22. Said pneumatic 20 is preferably secured to the top of the power pneumatic 3 and is controlled through a passage 50 30 formed in its fixed lower member 21, and also in the fixed member 3^a of the pneumatic 3. A tracker board tube 31 extends to the passage 30, being preferably fitted in an aperture formed in the member 3^a.

55 Passages 34—34 are also formed in each member 2, extending lengthwise of the same from the valve chamber 12 toward the member 1 and through passages 35—35 extending downwardly from the ends of the 60 passages 34—34 on opposite sides of the passage or duct 24 and communicating with the interior of the pneumatic 3.

Thus assuming the apparatus to be operated by means of reduced air pressure, a 65 partial vacuum being created in the mem-

ber 1 by means of the wind inducing apparatus, the operation of the device will be as follows. The small valve controlling pneumatic 20 will be normally collapsed so that the valve 13 will normally open the 70 port 15 and close the port 16. Air being admitted to a tracker board tube will pass into such tube 31 and into the passage 30 and thereby expand the pneumatic 20, causing the member 22 thereof to lift the valve 13 75 and close the passage 15 and open the passage 16. This establishes communication between the valve chamber 12 and the interior of the power pneumatic 3 by means of the ducts or passages 34—35, the result of which 80 is that the air is exhausted from the interior of said pneumatic 3 and the same is collapsed, thereby actuating the piano action or such other device as is to be operated by 85 said pneumatic 3. When air ceases to be admitted to the tracker tube 31, the small pneumatic 20 is collapsed through the operation of the bleed port 27 and the valve 13 is thereupon lowered and communication 90 closed between the valve chamber 12 and the interior of pneumatic 3, and the port 15 opened and air admitted through the same and into the valve chamber 12, and thence into the pneumatic 3 so as to expand said pneumatic. Air being again admitted to the 95 tracker tube 31 the pneumatic 20 will be again expanded, the valve 13 again elevated and air again exhausted from pneumatic 3, thereby collapsing said pneumatic and holding the same collapsed until air is shut off from the tracker tube 31 when pneumatic 100 3 will be again expanded.

It will be seen that the action is simple and compact, made with but few parts. For example each member 2 may be made 105 of a single piece or block of wood with the various passages and chambers bored or otherwise formed in it. Furthermore, the structure is very compact, occupying but little space. Furthermore, the power pneumatic 3 possesses great power and also quickness and sensitiveness of action, because of its being hinged or pivoted along its longitudinal edge, thus presenting a greater area to suction in proportion to the length 110 of the swinging member thereby obtaining a greater leverage and quickening of the response of the swinging member to suction.

115 In the modification shown in Figs. 5 to 8, 120 inclusive, the longitudinally extending windway member 1 is shown, and also members 2—2 attached thereto, as in the construction described in connection with Figs. 1 to 4, inclusive. These members 2—2 are provided 125 with valve chambers 12 containing valves 13 and also with small or supplemental pneumatics 21 arranged to operate the valves 13, all as previously described in connection with the other construction. 130

Below the members 2—2, however, are located and attached pneumatics 37 which are arranged crosswise of the member 1 and underneath and in contact with the same and also with the under side of the members 2—2. The pneumatics 37, however, are arranged to swing about one of their short ends, instead of about one of their long ends, as in the case of the pneumatics 3. Side ports 34^a and 35^a afford communication between the valve chambers 12 and interior of pneumatic 37, so as to control the same. Thus the longitudinally opening type of pneumatic 37 may be used with the remainder of the action, as well as the crosswise opening pneumatic 3 described in connection with the other apparatus.

It will be understood that changes and modifications may be made without departing from the spirit of the invention.

What I claim is:

1. The combination of a windway member, a valve holding structure at the side of the windway member and means for connecting said member and structure together comprising a tubular member fitted in one wall of the windway member and also fitted in the adjacent side of the valve containing structure, said tubular member also forming a duct between said windway member and the interior of said structure.

2. The combination of a windway member, a valve holding structure at the side of the windway member and means for connecting said member and structure together comprising a tubular member fitted in one wall of the windway member and also fitted in the adjacent side of the valve containing structure, said tubular member also forming a duct between said windway member and the interior of said structure, and means for drawing said member and structure together.

3. The combination of a windway member, a valve holding structure at the side of the windway member and means for connecting said member and structure together comprising a tubular member fitted in one wall of the windway member and also fitted in the adjacent side of the valve containing structure, said tubular member also forming a duct between said windway member and the interior of said structure, and means for drawing said member and structure together, said means comprising a rod connected with said tubular member and having a threaded end provided with a threaded nut for adjustment purposes.

4. The combination of a windway member, a valve holding structure at the side of the windway member and means for connecting said member and structure together comprising a tubular member fitted in one wall of the windway member and also fitted in the adjacent side of the valve contain-

ing structure, said tubular member also forming a duct between said windway member and the interior of said structure, and means for drawing said member and structure together, said means comprising a rod connected with said tubular member and having a threaded end provided with a threaded nut for adjustment purposes, said rod passing through the opposite wall of said windway member and having its threaded end and the nut thereon outside of said windway member.

5. In a pneumatic action the combination of a valve casing or chamber, a windway member in the form of a metallic tube 70 against the side of which the end of said valve casing is in contact, and means for detachably securing said valve casing to said windway member comprising a metal sleeve fitted in said valve casing, and a threaded rod extended through the windway member and provided with a thumb nut.

6. In a pneumatic action a power pneumatic having a hinged member hinged along 80 one of its long sides.

7. In a pneumatic action, a power pneumatic consisting of fixed and swinging members of substantially greater length than width and means for hinging said members 85 together along one of their longitudinal edges.

8. In a pneumatic action, a power pneumatic consisting of fixed and swinging members of substantially greater length than width and means for hinging said members 100 together along one of their longitudinal edges, said hinging means comprising a longitudinally extending member interposed between the hinged edges of said members so as to permit a greater amplitude of movement on the part of the swinging member.

9. In a pneumatic action, a structure comprising one of the members of an operating pneumatic, said pneumatic being of substantially greater length than width and being hinged upon one of its long sides.

10. In a pneumatic action, a structure comprising one of the members of an operating pneumatic, said pneumatic being of substantially greater length than width and being hinged upon one of its long sides, the long side of said member forming the under side of said pneumatic.

11. In a pneumatic action, a structure comprising one of the members of an operating pneumatic, said pneumatic being of substantially greater length than width and being hinged upon one of its long sides, the long side of said member forming the under side of said pneumatic and being inclined 120 from its hinged edge.

In witness whereof, I hereunto subscribe my name this 14th day of November, A. D. 1919.

ADOLPH P. GUSTAFSON.
